UNITED STATES PATENT OFFICE.

DALTON K. WILSON, OF WATERLOO, IOWA.

CONTROLLING MEANS FOR CULTIVATORS.

1,412,988.

Specification of Letters Patent. Patented Apr. 18, 1922.

Application filed June 18, 1920. Serial No. 389,887.

To all whom it may concern:

Be it known that I, DALTON K. WILSON, a citizen of the United States of America, and a resident of Waterloo, Blackhawk County, 5 Iowa, have invented certain new and useful Improvements in Controlling Means for Cultivators, of which the following is a specification.

My invention relates to improvements in 10 controlling means for cultivators and the like, and the object of my improvement is to provide means for permitting change of the direction of travel of the device with or without operatively shifting the implements 15 thereof, to thereby ensure complete manual control as desired of both simultaneously or in alternation.

This object I have accomplished by the means which are hereinafter fully described 20 and claimed, and which are illustrated in the accompanying drawings, in which Fig. 1 is a side elevation of my improved cultivator, with parts removed or broken away, and Fig. 2 is a side elevation of such a cultivator 25 with a modified form of implement controlling-means, parts also being removed or broken away, including the prime-motor and power transmission mechanism. Fig. 3 is a top plan view of the cultivator, with parts 30 removed. Fig. 4 is a rear elevation thereof, and Fig. 5 is a front elevation thereof, with parts removed or broken away.

In all said figures, similar numerals of reference denote corresponding parts throughout the several views.

My improved cultivator is preferably of the riding type, propelled by a prime-motor 22 mounted on the frame 9 thereof, but in principle, my improved controlling-means 40 for simultaneously or selectively operating the steering-wheels and the gangs may be applied to a machine of any other type, that is, propelled manually or by other power, and containing different working appliances or 45 implements.

The numeral 13 denotes a pair of independently-rotatable carrying-wheels upon which is supported and mounted a rigid skeleton frame made up of side-members 1 connected by cross-bars 2, 3 and 4. The side-bars 1 have rearward extensions numbered 5, 50 whose rear extremities are connected by a cross-bar 15 upon which a driver's seat 16 is medially positioned. From the frame depend rigid hangers 21, 55 and 7, which are

connected at their lower ends to the bars 20, the latter underlying the bars 1 and having their rear ends raised and secured to the rear ends of the bars 5. The stub-axles 8 of the carrying-wheels 13 have their inner ends 60 fixed in boxings (not shown) mounted in the spaced hangers 7, the wheels being rotatable on said fixed axles, and having mounted concentrically on their inner faces the sprocket-rims 17 driven by the sprocket-chains 35. 65

The prime-motor 22 is mounted on forwardly-extended parallel longitudinal bars 9 of said frame, which are connected at their forward ends by a hollow rectangular casting 11, and are braced by inclined brace-bars. Other brace-bars 10 also are connected between the forward parts of the bars 9 and the lower parts of the hangers 5, whereby a rigid but light frame construction is afforded. 70

The forward part of the frame is supported upon the pair of dirigible steering- or caster-wheels 14. These are mounted on pintle-shafts or axles 18 whose ends are mounted in bearing-openings in the lower 80 parts of spaced hangers 19. Between the upper ends of these hangers 19 are fixed a hollow block 79 having alined openings in its upper and lower parts to receive the diminished ends of a fixed pintle-body 78 85 whose upper end is secured in an opening in a block 80 secured upon the cross-bar 12, the latter being fixed across the two frame-members 9. From the upper part of each pintle 78 projects downwardly and rearwardly an arcuate integral arm 76, having on its lower extremity a longitudinally-ori-ficed body 77, in which is mounted the forward end of an upwardly and inwardly inclined brace-rod 75, secured by an adjusting 95 nut, and this rod 75 is alined with a radius of the wheel 14, thus giving increased support to same and to the pintle-block 78 which carries the other block 79. From the upper part of each block 79 projects rearwardly a short integral arm 81. 100

The numeral 82 denotes a pair of transversely-alined bars, whose outer ends are pivotally connected to the rear ends of the arms 81. On the inner ends of the bars 82 105 are fixed angle-plates 83, whose upstanding parts are orificed in line to receive the threaded ends of an adjusting-rod 84, secured by adjusting-nuts.

The numeral 71 denotes a pair of longi-

tudinally arranged tubular beams whose rear ends terminate in fixed risers 90 with handle-loops 73, as shown in Fig. 1. To the forward extremities of the beams 71 are fixed outwardly-curved arms 89, whose outer ends are pivotally connected at 88 to the outer ends of the transversely aligned bars or rock-arms 86, which have their inner ends pivotally connected at 87 to the cross-bar 12. The arms 86 have integral rearwardly-extending arms or branches 85 which are pivotally connected to the inner ends of the bars 82. The radii from the pintles 87 to the last-mentioned adjacent pivotal connections are each 15 equal in length to the length of each arm 81. The looped handles 73 of the controller-beams 71 are positioned conveniently in front of the seat 16 for manual operation by the driver, who may shift these controllers 20 longitudinally in order to simultaneously rock the wheels 14 laterally as desired to change the direction of movement of the machine.

A pair of gangs 60 having thereon stirrups 25 91 and 92 respectively are positioned longitudinally below the main frame, and their forward extremities have an universal-joint connection with the supporting hangers 21 and 55, and bar 20. This universal-joint 30 comprises a housing member fixed on the forward end of the gangs 60 carrying a pintle 58 which has rearwardly-extending lugs 57 pivoted at 56 to said supporting elements, whereby the gangs may be swung 35 laterally or up and down. On said gangs are mounted shanks 61 carrying shovels 62. I have shown in said Figs. 1 and 2 two variations of swinging-connections between the gangs and the controllers 71 thereabove. 40 These both come within the principle of my invention, which contemplates such a loose connection between said elements that the controllers may be operated in changing the direction of travel of the machine, or may 45 be used to simultaneously change such direction while otherwise shifting or moving the gangs.

In Fig. 1, a standard is swingingly erected upon the gangs and connected to the 50 controller-beam 71 above by a loose or universal joint. This standard may, as in said figure shown, comprise spaced bars 64 which are passed down on opposite sides of the gangs and have their lower extremities connected to a bearing-casting or block 64^a by means of a pintle-bolt 64^b. The upper ends of said bars are connected by a bolt, which in turn has a link-connection with the eye of an eye-bolt 64^a, the latter traversing the 55 beam 71 and secured thereto. I have supplied a yieldable resilient connection between the main frame and the two-part or bar standard 64, which consists of a coiled tension spring 67 whose forward end is connected to a bar 68. This bar 68 has a thread-

ed pin extension on its forward end which traverses an opening in a bowed bar 69 and is secured thereto by an adjusting-nut. This bowed bar is fixedly mounted on the hanger 55. The rear end of said spring is connected to a short bar 66, whose rear end is pivoted on a cross-bolt 65 of the standard-members 64, whereby the latter as also the gangs and the controller above are elastically supported. The connections between the ends of the standard 64 and the controller and the gangs are such as to permit of swinging of the gangs laterally or up and down, and in such a manner that the controller may be shifted to and fro longitudinally without 80 relatively moving the gangs.

In said Fig. 2, a similar result is effected. The numeral 93 denotes a short vertically-disposed standard fixedly mounted on the gangs 60, and a like tension spring is connected to its upper end. To the rear of this standard, a standard 72 is swingingly erected on the gangs. This standard may be a tubular member 72 having a fork 72^b at its lower end which encompasses the gangs 90 and is pivotally connected to a bearing-block 72^a on the gangs by means of a pivot-bolt 72^c. The upper part of the standard 72 has a looped handle 73 projecting rearwardly, and the standard is connected to 95 the rear extremity of the adjacent controller-beam 71 by means of a freely linked connection 72^d of the universal-joint type. This device also permits either separate use of the controller in changing the direction of 100 the machine, or the simultaneous coactions of the dirigible steering-wheels and the shifting as desired of the gangs.

The controlling of these actions selectively by the longitudinally movable controllers, is consonant to the usual method of control of such machines, whether power-propelled or animal-hauled, the operator's movements being normally longitudinal, which does not either directly or indirectly cause sidewise shifting of the gangs when the controllers are employed only for changing the direction of travel. The operator's attention is not disturbed, and the implements perform 110 more perfect work.

Having described my invention, what I claim as new, and desire to secure by Letters Patent, is:

1. In a device of the character described, carrying-wheels, dirigible steering-wheels, a 120 main frame mounted on said carrying-wheels, a gangs movably connected to said main frame, a longitudinally-movable controller operatively connected to said steering-wheels to change their direction of travel 125 only when shifted longitudinally, and a connecting element connected for swinging movements only at opposite ends with said controller and with said gangs respectively to permit using the controller to change the 130

direction of the steering-wheels with or without shifting the gangs.

2. In a device of the character described, carrying-wheels, a pair of dirigible steering-wheels, a main frame mounted over said wheels, a pair of gangs having their forward ends suspended movably from said main frame, a pair of longitudinally-movable controllers, relatively-movable linking-connections between said steering-wheels permitting them to be rocked laterally together, connecting-means between said linking-connections and said controllers, and a connecting element positioned between each controller and the adjacent gangs, loosely linked to both to permit manual use of the controller in changing direction of travel of the steering-wheels with or without also changing the positions of the gangs.

20 3. In a device of the character described, carrying-wheels, a pair of dirigible steering-wheels, a main frame supported thereon, a pair of gangs mounted on said main frame by universal-joint connections, a pair of controller-beams positioned longitudinally over said gangs, having their forward ends connected operatively with said steering-wheels to change their direction of travel when the beams are shifted longitudinally, a connecting-device positioned between each controller and the gangs thereunder and loosely interlinked with both, and an elastic member connected between each of said connecting-devices and the main frame.

35 4. In a device of the character described, carrying-wheels, a pair of dirigible steering-wheels, movable gangs, means of transportation therefor, a pair of movable controllers operatively connected with said steering-wheels to rock them simultaneously, when

only, and swiveled connections between said controllers and said gangs.

5. In a device of the character described, carrying-wheels, a pair of dirigible wheels, 45 movable gangs, movably supported by said carrying-wheels, a pair of controllers connected with said dirigible wheels to change their direction of travel when the controllers are shifted longitudinally, standards erected 50 upon said gangs to swing longitudinally, and swiveled for swinging movements, devices between said standards and said controllers permitting free play to the latter relatively to the standards.

55 6. In a device of the character described, carrying-wheels, a main frame mounted thereon, dirigible operatively connected steering-wheels, gangs swingingly connected to the main frame, and means for controlling the direction of travel of said steering-wheels having different hinged connections to said gangs and movable longitudinally to control the steering-wheels, also movable to control the gangs, either simultaneously or 60 in alternation.

65 7. In a device of the character described, carrying-wheels, a main frame mounted thereon, dirigible steering-wheels, gangs suspended movably from the main frame, 70 controller-beams positioned longitudinally over said gangs, operative connections between said controller-beams and said steering-wheels, standards connected hinged to the controller-beams, and also connected 75 hinged to the gangs, the first-mentioned connections being universal-joints, and elastic connections between said main frame and said gangs.

Signed at Waterloo, Iowa, this 21st day of 80
May, 1920.

DALTON K. WILSON.
